UNITED STATES PATENT OFFICE

2,233,332

DISPENSING CONTAINER

Lewis E. Wagner, Honolulu, Territory of Hawaii

Application September 7, 1939, Serial No. 293,817

2 Claims. (Cl. 248—311)

The present invention relates to dispensing containers and is particularly adapted for household use in dispensing wax paper.

At the present time wax paper in rolled form is packaged in a carton that is formed with a metallic serrated edge for severing portions of the paper as it is dispensed therefrom. It is an object of the present invention to provide a container that will effectively hold the entire package of wax paper in a manner for convenient dispensing of the paper as it is needed.

A further object of the invention is to provide a dispensing container which will be strong and durable, pleasing in appearance to conform to the surroundings in which it is used, yet economical to manufacture.

The invention will be fully and comprehensively understood from a consideration of the following detailed description when read in connection with the accompanying drawing which forms a part of the application.

In the drawing:

Figure 1 is a perspective view of the dispensing container with the package removed therefrom.

Figure 2 is a top plan view of the blank from which the container is formed.

Figure 3 is a front elevational view of the container having a package of wax paper disposed therein, and

Figure 4 is a vertical sectional view taken substantially on line 4—4 of Figure 3.

Referring to the drawing, the numeral 5 generally designates a dispensing container constructed in accordance with the present invention. The container 5 is preferably formed of sheet metal and comprises a rear wall 6, bottom wall 7, and end walls 8 and 9 all of integral formation. The bottom wall 7 extends at right angles to the rear wall 6 being folded, during fabrication, on the line 10. The ends of the bottom wall 7 are formed with lapped portions 11 adapted to be welded or otherwise secured on the inside of the end walls 8 and 9. Providing the lapped portions 11 not only simplifies the construction of the die used to cut out the blanks but also serves to strengthen the container by welding or otherwise securing said portions to the end walls.

The end walls 8 and 9, respectively, extend forwardly beyond the front edge of the bottom wall 7 as shown, and have their front edges 12 inclining downwardly and rearwardly to provide flaps 13 for retaining the package 14 within the container. From a point on a line with the front edge of the bottom wall 7, the end walls 8 and 9 are cut so as to be inclined as indicated at 15 with the upper edge of the flaps 13 inclin-

ing in opposite directions as indicated at 16 to form the flaps in the manner shown.

The rear wall 6 is provided with openings for the reception of fastening elements 17 for securing the container to a wall or other suitable support 18.

In Figures 3 and 4 of the drawing there is disclosed a conventional package 14 containing a roll of wax paper 18 and it will be noted that the package is placed within the container so that its serrated cutting edge 20 extends downwardly. The wax paper is dispensed between the wall 21 of the package and the serrated cutting edge 20 and is severed by means of the cutting edge as needed. The package 14 snugly fits within the container 5 being securely held by means of the end walls 8 and 9 and their integrally formed flaps 13. The flaps 13 may be bent inwardly or outwardly when placing or removing a package therefrom and the bending of the flaps 20 inwardly will serve to securely retain the package in position.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. A dispensing container for a package of rolled wax paper, comprising, a back wall formed with openings for receiving fastening elements to attach said container to a support, a bottom wall integral with and extending at right angles to said back wall, end walls integral with said back wall and having their front edges inclining downwardly and rearwardly to form flaps for retaining the package within said container.

2. A dispensing container for a package of rolled wax paper, comprising, a back wall formed with openings for receiving fastening elements to attach said container to a support, a bottom wall integral with and extending at right angles to said back wall, end walls integral with said back wall, said end walls extending forwardly beyond the front edge of said bottom wall and having their front edges inclining downwardly and rearwardly for retaining the package within said container.

LEWIS E. WAGNER.
